United States Patent Office.

JOHN G. ROTH, OF NEW YORK, N. Y.

Letters Patent No. 79,502, dated June 30, 1868.

IMPROVED CLOTHES-PIN.

The Schedule referred to in these Letters Patent and making part of the same.

TO ALL WHOM IT MAY CONCERN:

Be it known that I, JOHN G. ROTH, of New York, in the county of New York, and State of New York, have invented a new and useful Improvement in Clothes-Pins; and I do hereby declare that the following is a full, clear, and exact description thereof, which will enable others skilled in the art to make and use the same, reference being had to the accompanying drawings, forming part of this specification, in which—

The figure is a side view of my improved clothes-pin.

Similar letters of reference indicate like parts.

My invention has for its object to furnish an improved clothes-pin, simple in construction, not liable to get out of order, and reliable in operation, holding the clothes securely, and so constructed as to securely hold the most delicate fabrics without its being necessary to put the said fabrics over the clothes-lines.

It consists in the construction and combination of the various parts of the clothes-pin, as hereinafter more fully described.

A A are the main parts or levers of the pin, which are made exactly alike, and in substantially the shape and manner shown in the figure.

The parts A are formed with shoulders a^1 , at or a little above the middle parts of their inner sides, to form a support to the rubber-block spring B, which is placed between the upper parts of the said parts A, just above and resting upon the shoulders a^1 . The inner sides of the upper end of the parts A are rounded off, so that the upper ends of said parts may be pressed together to open the lower ends or jaws of the pin.

Just below the shoulders a^1 , upon the inner sides of the parts A, are formed the notches a^2 , to receive the clothes-line. The notches a^2 are elongated or extended downward, as shown in the figure, terminating in an abrupt shoulder, the lower part of the slot thus formed, being narrower or more contracted than the upper part that receives the clothes-line.

The lower parts or jaws a^3 of the parts A, are so formed as to rest against each other, as shown in the figure.

The parts A are connected to each other by the wire band or ring C, or by any other suitable device, at a point below the rubber-block B, and above the notches a^2 , as shown in the figure, said band or ring C holding the parts A and B in their proper relative positions, and forming the pivoting points of the said parts A.

In using the pin for the coarser articles, the article to be secured upon the line is put over it, and the pin applied in the ordinary manner, clamping the article to the line, but in the case of more delicate articles, the pin alone is put over the line, said line resting in the upper and larger parts of the slot formed by the notches a^2 . The article to be held is then placed between the jaws a^3 , its upper edge or hem entering the lower or narrower parts of said slot a^2 , so that the shoulders at the upper end of the jaws a^3 may prevent the said article from working out of the pin.

The India-rubber block or spring is self-retaining between two planes formed on contiguous sides of the levers A, at a convenient distance back of joint or axis of their motion. The quadrangular form of the piece of rubber serves the important purpose of maintaining the two levers on the same plane, or parallel with each other, both when the spring is compressed in action, or at rest, thereby obviating the tendency to lateral and irregular motion with relation to each other, which impairs the efficiency of the article as a clamp, and causes wear upon the connecting parts of the joint.

The ordinary pressure of the levers upon the rubber spring, when properly connected, is sufficient, with the friction of rubber against wood, to prevent the spring from being lost out, and therefore I do not form notches for its reception, which is unnecessary, and entails additional cost in the manufacture, besides being positively injurious, in that they weaken the wood in the proportion of the amount removed, making it liable to break at the point where it is subjected to the greatest strain, where the rubber forms, when the clamp is opened, the fulcrum-bearing of the lever-handles.

To recapitulate, the described improvement consists in constructing clothes-line clamps, commonly termed "clothes-pins," with a quadrangular rubber spring-block, in combination with contiguous planes at a suitable distance from the axis of two connected levers, said planes being parallel with each other, and with the sides

of the spring-block in a transverse direction, and parallel or nearly so in a longitudinal direction, and also in forming the jaws with a graduated recess, diminishing from the ordinary diameter of a large-sized clothes-line to that of the smallest cord that can be advantageously employed, said recess terminating at the smaller extremity with abrupt shoulders, to enable clothing to be held upon a small line without pulling off, or by the shoulders alone, and also to prevent the cord from slipping from the jaws of the clamp.

I do not claim a band or link surrounding the two parts of the clamp, nor do I claim these parts when formed with notches, sockets, or a recessed seat for the rubber spring, such construction, however necessary or useful in other clamps, not being applicable to the principle of construction on which my invention is based, and consequently positively injurious if combined therewith.

What I claim as my invention, is—

In a clothes-line clamp formed of two jointed levers, provided with parallel or nearly parallel contiguous bearing-planes, the quadrangular self-retaining rubber spring-block, arranged and operating substantially as and for the purposes set forth.

I also claim in a clothes-line clamp formed of two jointed levers A A, the abruptly-terminating jaw-recesses a^2 a^2 , arranged and operating substantially in the manner and for the purposes set forth.

The above specification of my invention signed by me, this fourteenth day of April, 1868.

JOHN G. ROTH.
